(57) **CLAIM**

The ornamental design for a racket head surface pad as shown and described.

DESCRIPTION

FIG. 1 is a perspective view of a racket head surface pad in use;

FIG. 2 is a front view thereof;

FIG. 3 is a rear view thereof;

FIG. 4 is a right side view thereof, the left side being identical;

FIG. 5 is a top plan view thereof; and,

FIG. 6 is a bottom plan view thereof.

The broken lines in the drawings depict portions of the racket head surface pad and environment that form no part of the claimed design.
